UNITED STATES PATENT OFFICE.

CHARLES E. ANDERSON, OF GRAND RAPIDS, MICHIGAN.

NICOTIN-STILL.

1,277,817.

Specification of Letters Patent. Patented Sept. 3, 1918.

Application filed May 10, 1918. Serial No. 233,755.

To all whom it may concern:

Be it known that I, CHARLES E. ANDERSON, a citizen of the United States of America, residing at Grand Rapids, in the county of Kent and State of Michigan, have invented certain new and useful Improvements in Nicotin-Stills; and I do hereby declare the following to be a full, clear, and exact description of the invention, such as will enable others skilled in the art to which it appertains to make and use the same.

This invention relates to an apparatus for distilling nicotin from tobacco. It is the primary object and purpose of this invention to provide a relatively simple yet compact device in which tobacco may be burned and nicotin collected from the products of combustion thereof. For an understanding of the invention by which this result is obtained, reference may be had to the accompanying drawing showing a preferred type of construction embodying the same in which.

Figure 1 is an elevation of the apparatus, parts being broken away and shown in section to better disclose the construction.

Fig. 2 is a vertical section through the same.

Fig. 3 is a plan view of the complete apparatus, the cover to the inner receptacle being removed, and

Fig. 4 is a fragmentary vertical section taken through the pump mechanism which is attached to the device for drawing the products of combustion through the same.

Like reference characters refer to like parts in the different views of the drawing.

In construction an outer receptacle, preferably of cylindrical form, having sides 1 and a bottom 2 is provided, the same being supported in any suitable manner as by legs 3, though any other type of support may be used. Within the same a receptacle 4 of smaller diameter having cylindrical walls 4 and a downwardly curved bottom 5 is positioned, being held in any suitable manner a short distance above the bottom 2 of the outer receptacle and having its walls spaced a distance from the walls 1 of the outer receptacle. The entire space between the two receptacles may be filled with water. A member 6 having a passage therethrough is connected to the bottom 5 and extends through the bottom 2 of the outer receptacle, communicating with which is a collecting

jar 7, preferably of glass. A coil 8 is coupled at one end with the member 6 and is turned around the inner receptacle 4 to the upper end thereof, its upper end extending beyond the outer receptacle 1 and connecting with the flared end 9 of a box 10, which is provided with a downwardly curved bottom 11 and with a cover 12, as shown. A collecting receptacle or jar 13 is connected to the bottom 11 and communicates with the interior space thereof and, similarly, an inverted jar 14 is connected to the cover 12 as shown. At a short distance from each end of the box 10, wire screens 15 are mounted, between which and the ends of the box, any suitable collecting sponge material 16 is placed, the space between the two screens 15 being left open; and it is with this space that the jars 13 and 14 communicate.

A fan casing 17 in which a rotary fan 18 is mounted is attached to the box 10, any suitable valve 19 being interposed in the connection between said casing and box. The fan casing has an outlet 20 as shown. The jar 14 is of utility as it provides an additional space above the box 10 communicating with the interior space therein for holding the product of combustion and for condensation thereof, such condensation taking place with greater rapidity by reason of the relatively lower temperature of the jar from its position above the box where it is exposed directly to the atmosphere at ordinary temperatures. This is particularly true when tobacco containing moisture is burned, the vapor therefrom rising into the jar and condensing quickly.

The inner receptacle is provided with a cover 21 over which any suitable perforated plate 22 may be placed, it and the portion 23 of the cover directly below it having openings 24 for the passage of air. The plate 22 is pivotally mounted on the cover and may be turned to more or less close the openings as may be desired.

Within the inner receptacle 4, a cylindrical member 24 of sheet metal having a flat perforated bottom 25 may be placed, this member being used to contain tobacco which may be lighted and the products of combustion therefrom drawn downwardly through the openings in the bottom 25 into the coil 8, and thence through the box 10 and the sponges therein, through the pump, and passed out through the outlet 20. The pump

may be driven in any suitable manner, as by an electric motor.

When the pump is operated, it is apparent that a draft is made to supply air to the burning tobacco, the air coming through the openings 23 heretofore described. The products of combustion pass through the member 6 and the coil 8 and, as the coil is surrounded by water the nicotin, which has been vaporized on burning the tobacco, partially condenses and runs downwardly through the coil and is collected in the jar 7. That part which is not thus condensed and collected, passes through the box 10 and is collected in the sponges 16 from which it may pass under the screens 15 to the jar 13. Practically all of the nicotin that is vaporized on burning the tobacco is collected in this manner. The remaining products of combustion which do not condense pass through the fan and outwardly through the outlet 20. The jars 7 and 13 are detachably connected in place so that the same may be readily removed at any time to empty their contents.

From the foregoing it will be apparent that I have provided an apparatus for obtaining nicotin from burning tobacco which is of relatively simple yet effective construction, and one in which substantially all of the nicotin may be secured in spite of the well known undependability of nicotin with respect to its properties of vaporizing when heated. The smoke in which the nicotin is carried is cooled as soon as it passes to the coil 8 to a point below the lowest point at which nicotin can vaporize, and there is no danger of a loss of nicotin from vaporization with a consequent passing out through the outlet 20. These features make the apparatus one of value. Many slight changes in minor detail of construction may be resorted to without departing from my invention and I, accordingly, consider myself entitled to all such modifications of structure which fall within the scope of the appended claims defining the invention.

I claim:

1. In a device of the character described, an outer receptacle, an inner receptacle located within the outer receptacle, a coil connected with the bottom of the inner receptacle and wound around the same, a collection receptacle depending from said receptacle and communicating with the coil, means for holding a quantity of tobacco within the inner receptacle, and means for drawing the products of combustion from the tobacco, when lighted, through the coil, substantially as described.

2. In a device of the character described,

a receptacle adapted to receive tobacco, a conduit leading from the bottom thereof, a collection receptacle attached to the lower end of the conduit, a coil connected to and communicating with the conduit, said coil being wound around said receptacle, means for drawing the products of combustion from the tobacco, when lighted, through the coil, and means for cooling the coil, substantially as described.

3. In a device of the character described, a receptacle adapted to hold tobacco, a conduit leading from the bottom thereof, a collection receptacle attached to the lower end of the conduit, a coil connected at its lower end to and communicating with said conduit, said coil being wound upwardly around said receptacle, a box to which the upper end of the coil is connected and into which it leads, sponge material inside the box, a second collection receptacle connected to the bottom of the box, means for drawing the products of combustion of the tobacco, when lighted, through the coil and box, and means for cooling the coil, substantially as described.

4. In a device of the character described, a receptacle adapted to hold tobacco, a conduit leading from the bottom thereof, a collection receptacle attached to the lower end of the conduit, a coil connected at its lower end to and communicating with said conduit, said coil being wound upwardly around the receptacle, a box into which the upper end of the coil leads, a screen located in the box a distance from each end thereof, sponges disposed between the screens and the ends of the box, a second collection receptacle connected to the bottom of the box at a point between said screens, and means to draw the products of combustion of the tobacco, when lighted, through the coil and box, substantially as described.

5. In a device of the character described, a receptacle having a downwardly curved bottom, a conduit leading therefrom, a collection receptacle detachably connected to the lower end of the conduit, a cover to the receptacle, said cover having vent openings therein, means movably mounted on the cover for opening and closing said openings, a tobacco container mounted in the receptacle having a perforated bottom, a coil connected to the conduit and wound upwardly around said receptacle, means for drawing the products of combustion from the tobacco, when lighted, through the coil, and means for cooling the coil, substantially as described.

In testimony whereof I affix my signature.
CHARLES E. ANDERSON.
